UNITED STATES PATENT OFFICE.

RICHARD J. KULISCH, OF ADAMS, ILLINOIS.

DISK ATTACHMENT FOR PLOWS.

1,162,934.

Specification of Letters Patent.

Patented Dec. 7, 1915.

Application filed June 28, 1915. Serial No. 36,844.

To all whom it may concern:

Be it known that I, RICHARD J. KULISCH, a citizen of the United States, residing at Adams, in the county of Adams and State 5 of Illinois, have invented certain new and useful Improvements in Disk Attachments for Plows, of which the following is a specification, reference being had to the accompanying drawings.

10 My invention relates to agricultural devices, and particularly to harrow attachments for plows.

The primary object of my invention is the provision of a very simple attachment adapted to be applied to the beam of an ordinary plow and adapted to support a plurality of disks.

15 A further object of my invention is to so mount the disks that they may be disposed in adjusted relation and at various angles to the beam.

Still another object is to so construct the attachment that it may be readily taken apart for the removal or replacement of the 20 disks.

Still a further object is to provide improved means for rotatably supporting the disks.

Other objects will appear in the course of 25 the following description.

My invention is illustrated in the accompanying drawings, wherein:

Figure 1 is a side elevation of my harrow attachment applied to a plow beam; Fig. 2 is 30 a rear elevation of the same, partly in section, the plow beam being also in section; Fig. 3 is a side elevation of one of the harrow disks showing its attachment to the hub; Fig. 4 is a section on the line 4—4 of 35 Fig. 1; and Fig. 5 is a side elevation of one of the hub sections detached.

40 Referring to these drawings, 2 designates the beam of a plow of any suitable character or the beam of a cultivator. Disposed against one face of the beam is a beam clamping plate which is designated 3. This plate is provided with openings for the passage of clamping bolts 4, and 5 is the plate on the side of the beam opposite the plate 3 45 through which the bolts 4 pass. The plate 3 has oppositely disposed bearings for the reception of the upper end of a crank arm 6, and passing through the plate 3 at a plurality of points are set screws 7, which, when 50 set up, bear against the vertically disposed portion of the crank arm 6 and hold the

crank arm in an adjusted position within the clamping plate. The middle of the crank arm is outwardly bent and then downwardly extended and is provided with spaced collars 60 8 and 9, each of these collars being formed with set screws whereby they may be adjusted upon the depending portion of the crank arm.

Disposed on each side of the depending 65 portion of the crank arm are the downwardly and rearwardly extending wheel supporting members or standards 10. As shown, there are two of these standards and the upper end of each standard is inwardly 70 bent and then formed with a semicylindrical seat 11. The upper ends of the standards confront each other and the seats receive the depending portion of the arm 6. Clamping bolts 12 and 13 pass through the ends of the 75 standards on each side of the seats and clamp the standards securely in place. These clamping bolts may be set up tightly enough so as to prevent any rotation of the standards upon the depending portion of the arm 80 6 or they may be relatively loose and allow of rotary movement of the standards upon the arm. The collars 8 and 9, previously referred to, are for the purpose of preventing vertical movement of the standards with relation to the depending portion of the crank arm, and by means of these collars the standards may be adjusted vertically. 85

The standards 10 extend downward and rearward and each terminates in a head 14, 90 each head having a central passage with flared ends. The hub upon which the cultivator disks are mounted, as illustrated, is formed in four sections. Each of these sections is designated 15. The middle disk 16 95 is clamped between two of these sections, while the end disks 17 are each clamped against the outer face of one of the sections. Each section comprises a disk-like portion 18 having a conical hub 19 projecting from 100 the inner face, the hub terminating in a cylindrical portion 20. At its edge the disk-like portion 18 is provided with a relatively thin extension 21 perforated for the passage of bolts or rivets. To support the middle 105 disk 16, two of these sections 15 are disposed one on each side of the disk and confronting each other and bolted to each other by bolts or rivets 22 which pass through the relatively thin marginal portions of the disks 21. 110 Each of the disks 17 is disposed against the flat face of the corresponding section 16 and

bolted thereto by bolts passing through the margin of the section. All of the members 15 are axially perforated for the passage of a main bolt 23. It will be seen that as the 5 hub of each disk is conical wear may be taken up from time to time by tightening up upon the bolt 23. Each of the heads 14 is formed with an oil hole 24 which extends down into the bearing formed on the head 10 and extends upward to the exterior of the head and terminates in an oil cup 25.

It will be seen that by removing the collars 8 and 9 the standards may be readily released from the crank arm 6, and that by 15 removing the bolts 12 and 13 the standards may be separated from each other, and if the bolt 23 is likewise removed the separation of the standards will permit a separation of the several hub sections of the several disks.

20 This permits the ready removal of the disks for grinding or substitution and permits the ready replacement of the disks. The disks themselves may be readily removed each from its hub section by loosening the bolts 25 22. It will be obvious that the angle of the disks to the plow beam may be readily adjusted by adjusting the crank arm 6 and that the disks may be raised or lowered to any desired position and held in their adjusted relation. It may be said that in actual 30 use the disks are twelve inches in diameter and are designed to be set 4 inches apart for 12 inch plows, $4\frac{1}{2}$ inches for 14 inch plows, and $5\frac{1}{2}$ inches apart for 16 inch plows. 35 Instead of using bolts 22 I may rivet the disks to the hub sections.

This attachment may be used on walking plows, gang plows, or tractor driven plows,

Copies of this patent may be obtained for five cents each, by addressing the "Commissioner of Patents, Washington, D. C."

and is of particular advantage inasmuch as the ground is immediately harrowed or sliced 40 by the disks, thus eliminating the necessity of disk-harrowing the soil after plowing.

Having thus described my invention, what I claim is:

In a disk attachment for plows, a vertically disposed supporting member, oppositely disposed standards, said standards converging at their upper ends and being formed each with a seat partially embracing the supporting member, means for clamping the standards to the supporting member, the outer ends of the standards being formed with enlarged heads, each head having a transverse opening flared at its ends, a harrow disk disposed between the standards 55 having oppositely disposed hub sections attached to its opposite faces, each hub section having a disk-like portion, a central conical portion and a cylindrical extension, and a harrow disk disposed exterior to each standard and each formed upon its inside face with a hub comprising a disk like portion and a central conical portion with a cylindrical extension, said conical portions and cylindrical extensions of the several hub sections being disposed within the openings in the heads, and a bolt passing through all of the hub sections and binding the disks in place upon the standards.

In testimony whereof I hereunto affix my 70 signature in the presence of two witnesses.

RICHARD J. KULISCH.
